UNITED STATES PATENT OFFICE.

FREDERICK FRASER MILLER, OF NAPANEE, ONTARIO, CANADA.

OIL BURNER.

Application filed February 24, 1921. Serial No. 447,613.

To all whom it may concern:

Be it known that I, FREDERICK FRASER MILLER, a subject of the King of Great Britain, residing at Napanee, in the county 5 of Lennox and Addington and Province of Ontario, in the Dominion of Canada, have invented new and useful Improvements in Oil Burners, of which the following is a specification.

10 My invention relates to improvements in oil burners for use in furnaces and boilers. In the use of fuel oil in house furnaces and small boilers the opening in the fuel nozzle of the burner requires to be large enough so 15 as not to clog up and with continuous burning such a nozzle will use an excessive amount of oil over the heating requirements of the furnace or boiler.

The object of my invention is to intermittently burn the fuel and so reduce the consumption without using a separate lighting flame or pilot light. I attain this object by the means illustrated in the accompanying drawing which illustrates the use in an ordinary hot water heater or furnace for a house.

Similar figures relate to similar parts throughout the drawing—

15 "1" is a combustion chamber inside the fire box of the furnace "3." It consists of a shell "A" lined with heat-resisting and nonconducting material or materials such as a carbon or fire clay refractory brick, backed with a nonconductor of heat such as asbestos "5" and supported upon a stand "4" and is shown in two halves held together by lugs "6" and "7" and bolts "2." By this means the parts can be made small enough to be placed in a furnace already set up, through the coal door "G" or ash door "H" 20 and it can also be easily taken apart so as to renew the lining "5." I do not restrict it to the use of a shell as "A" may consist of bolts and rods sufficient to hold the different parts of "5" together or to the use of a separator shell as in constructing a new furnace the shell "A" could be made an integral part of the furnace and is not necessarily contained in the fire box of the boiler or furnace but may connect outside so that the products 25 of combustion enter the fire box. "8" is an opening into "1" through which the air nozzle "9" containing the fuel nozzle "10" enters the chamber. "11" is a door closing

an opening "12" into "1" through which the initial fire is started "13," "13," "13," are 30 openings near the bottom of "1" to allow the products of combustion to escape out into the fire box of the furnace and are placed near the bottom so that when the fire is not burning the radiation of heat out 35 of "1" is reduced to a minimum. "14" is a pipe connecting "9" to an air blower "15" operated by an electric motor "17" resting upon a base "16." "E" is the body of the burner nozzle "10" having an adjusting 40 handle "D" and connected by a pipe "20" to the fuel tank "21" having a filler opening "22" and a pressure gauge "23." The pipe "20" has a hand valve "f" and passes through a valve "25" which is operated by an electric current being open when the current is on. "27" is an intermittent electric switch having conducting segments "29" "29" connected together by wires "30" with spaces "31" between. "26" is an electric conducting 45 hand operated by a train of clock work and by means of the wire "28" connects the segments "29" to the motor "17." "32" is a wire connecting "29" to one of the wires "C" of a source of electric supply. "33" is 50 a wire connecting "25" with the other wire "C" of the electric supply. "34" is a wire connecting "25" to "17." "35" is a wire connecting "28" and the motor "17" to an electric switch 24 controlled by the temperature of the furnace or house and thence to the wire "C."

The operation of the different parts is as follows:

55 After the fuel is placed in "21" and under pressure, a piece of lighted waste can be thrown into the chamber "1" through "11" and "12" and the electric current turned on and valve "F" opened. The motor "17" would be connected to electric supply on 60 one side by "34" and "35" through "25" and in the other side by either or both wires "32" and "35", "32" through "27" and "28" and "35" through switch "24". The valve "25" is immediately opened by the electric 65 current and fuel flows to the nozzle "10" at the same time. The motor "17" starts "15" and blows an air blast to the nozzle "9", the fuel is at once lighted by waste and goes on burning until both the switches "27" 70 and "24" cut off the current "27" because the

hand "26" is over a space "31" and "24" because the temperature of the house or boiler is high enough. "25" would at once cut off the fuel and "17" would stop. As chamber 5 "1" is lined with a heat-resisting and non-conducting material the temperature inside will be above and will stay above the flash point of the fuel for some time, and before it drops below such a point the switch 10 "27" is so adjusted as to cut in the current and the heat of the chamber will at once ignite the fuel and which by the adjustment of "27" will stay lighted long enough to reheat the chamber "1". The spaces "31" 15 and segments "29" and time of turning of "26" are adjusted so as to keep the temperature in "1" above the flash point of the fuel. At the same time if the temperature of the boiler or house drops below the pre- 20 determined point the switch "24" will cut in the current round the switch "27" and operate the burner until such temperature is reached. The switch "27" is then used to 25 keep the temperature of chamber "1" above the flash point of the fuel while the switch "24" controls the temperature of the boiler or house.

I do not restrict myself to the use of any special kind of a spray nozzle or intermittent switch or thermostatically operated switch or motor or air blower. Any one of several different forms may be used and the device illustrated is to be considered as being merely an exemplification of my invention.

I have sought to set forth the principle of my invention and the best mode in which I at present contemplate using that principle.

40 I am aware that an intermittent oil burner using a gas pilot light has been used. I

therefore do not make such a claim broadly but:—

I claim:

1. An apparatus, using liquid fuel for generating heat, for use with a furnace or a boiler, and being a combination of a combustion chamber made of heat resisting and non-conducting material or materials, and so constructed, with reference to the furnace or boiler, as to retain within itself a self firing degree of temperature for some time after the fuel is cut off, with means for spraying a fuel mixture into the combustion chamber, and with means for intermittently cutting on and off the fuel mixture in such a manner that it is on often enough and long enough, to keep the temperature of the combustion chamber at all times above the firing point of the fuel mixture, all substantially as described.

2. An apparatus, using liquid fuel for generating heat, for use with a furnace or a boiler, and being a combination of a combustion chamber made of heat resisting and nonconducting material or materials, and so constructed, with reference to the furnace or boiler, as to retain within itself a self firing degree of temperature for some time after the fuel is cut off, with means for spraying a fuel mixture into the combustion chamber, with means for intermittently cutting on and off the fuel mixture in such a manner that it is on often enough and long enough, to keep the temperature of the combustion chamber at all times above the firing point of the fuel mixture, and with means for automatically controlling the supply of fuel mixture so as to meet the exigencies of the furnace or boiler, all substantially as described.

FREDERICK FRASER MILLER.
